UNITED STATES PATENT OFFICE.

JOSEPH GRAVES, OF KNOBNOSTER, MISSOURI.

ROTARY ENGINE.

SPECIFICATION forming part of Letters Patent No. 736,383, dated August 18, 1903.

Application filed June 22, 1903. Serial No. 162,568. (No model.)

To all whom it may concern:

Be it known that I, JOSEPH GRAVES, a citizen of the United States, residing at Knobnoster, in the county of Johnson, State of Missouri, have invented certain new and useful Improvements in Rotary Engines; and I do hereby declare the following to be a full, clear, and exact description of the invention, such as will enable others skilled in the art to which it appertains to make and use the same.

This invention relates to rotary engines, and particularly to the class of impact rotary engines, the object of the invention being to provide an engine which will be extremely simple in construction and in which the piston-head will be so mounted as to insure against leakage of steam between them and the cylinder-head.

Other objects and advantages of the invention will be understood from the following description.

In the drawings forming a portion of this specification, and in which like numerals of reference indicate similar parts in both views, Figure 1 is a vertical section through the engine at right angles to the piston-shaft. Fig. 2 is a vertical section at right angles to Fig. 1.

Referring now to the drawings, the present engine consists of a cylinder including the ring 5, against the ends of which are bolted the heads 6 and 7, packing-rings 8 and 9 being disposed between the ends of the ring and the head to prevent leakage of steam. In the head and centrally thereof are the bearings 10 and 11, in which is mounted the shaft 12, which carries the piston. The piston consists of a number of metal plates, which in the present instance are three in number and are shown at 11, 12, and 13. The plates 11 and 13 are of substantially V shape, the extremities thereof being curved in the same direction, while the plate 12 has the shape of a compound curve from end to end. The piston-shaft has an angular hub 14 formed thereon, and against one side face of this hub is disposed the bight portion of the plate 11, the plate 12 being disposed against the opposite face of the hub, while the U-shaped plate

13 is disposed with its bight portion against the plate 12. To hold these several plates to the hub of the shaft, a bolt 15 is engaged through the several plates and through the hub, so that the plates may have a slight pivotal movement, it being noted that the free ends of the several plates are substantially equidistant rotatably of the shaft. The several plates of the piston are of the same width and in their side edges are channels 16, in which are disposed packing-strips 17, which are pressed outwardly against the inner faces of the cylinder-heads by the action of the springs 18, so that the packing-strips are in close contact with the cylinder-heads. This arrangement of the packing-strips, together with the pivotal mounting of the plates of the piston, insures against leakage of steam between the sides of the plates and the cylinder-heads.

In the upper side of the ring 5 of the cylinder is an inlet-port 19, with which is connected a steam-supply pipe 20, from which the steam is directed against the piston heads or wings formed by the ends of the plates 11, 12, and 13, the outlet-port 21 being formed at the bottom of the ring 5, with which is connected an exhaust-pipe 22.

In the operation of the engine the steam strikes against the piston heads or wings and by its impact repels them, and thus rotates the shaft, the heads or wings, with the spring-pressed packing-strips, accommodating themselves to any unevenness due to wear or other cause, so that escape of steam and low efficiency are provided against.

It will be understood, of course, that any suitable motive fluid may be employed to operate the motor.

What is claimed is—

1. In a rotary engine, the combination with a cylinder, of a shaft rotatably mounted therein and piston-heads pivoted to the shaft and movable at right angles to the heads of the cylinder, the piston-heads having packing-strips slidably engaged in their side edge portions and provided with means for holding them normally and yieldably projected.

2. In a rotary engine, the combination with a cylinder, of a shaft rotatably mounted therein, piston-heads formed integral in pairs and pivoted to the shaft for movement at right angles to the cylinder-heads, said piston-heads having grooves in their side edges, packing strips movably mounted in the grooves of the piston-heads, and means for holding said

packing-strips in yieldable contact with the cylinder-heads.

In testimony whereof I affix my signature in presence of two witnesses.

JOSEPH GRAVES.
